UNITED STATES PATENT OFFICE.

HERMAN P. RUF, OF NEW YORK, N. Y.

DESIGN FOR A COMBINED ASH TRAY, CIGAR HOLDER, AND DRILL.

Application filed May 4, 1928. Serial No. 26,566. Term of patent 7 years.

To all whom it may concern:

Be it known that I, HERMAN P. RUF, a citizen of the United States, residing in New York city, borough of Manhattan, in the county and State of New York, have invented a certain new, original, and ornamental Design for Combined Ash Trays, Cigar Holders, and Drills, of which the following is a specification, reference being had to the accompanying drawings, forming a part thereof, and of which—

Figure 1 is a side elevation, Fig. 2 is a front elevation, and Fig. 3 is a top plan view of an ash tray, cigar holder, and drill showing my new design.

I claim:

The ornamental design for a combined ash tray, cigar holder, and drill, as shown.

HERMAN P. RUF.
